WITNESS:

UNITED STATES PATENT OFFICE.

JOHN W. McGILVRAY AND JOSEPH WELLERSDICK, OF TORRINGTON, CONNECTICUT.

IRON.

1,403,432.

Specification of Letters Patent. Patented Jan. 10, 1922.

Application filed April 9, 1921. Serial No. 460,072.

To all whom it may concern:

Be it known that we, JOHN W. McGILVRAY and JOSEPH WELLERSDICK, citizens of the United States, residing at Torrington, in the county of Litchfield and State of Connecticut, have invented new and useful Improvements in Iron, of which the following is a specification.

Our present invention has reference to improvements in electrically heated sad irons.

An object of the invention is to improve the general construction of this class of devices by producing a sad iron provided with a core of heat retaining property secured to the base and to the outer casing of the iron in a novel manner.

A further object is to provide in an electrically heated sad iron thermostatically influenced means for indicating the exact temperature of the iron and whereby the operator can properly employ the device upon varying qualities and classes of goods to be ironed which require an iron heated at different degrees for proper operation thereon.

The foregoing, and other objects which will appear as the nature of the invention is better understood, may be accomplished by a construction, combination and operative association of parts, a satisfactory embodiment of which being disclosed by the drawings which accompany and which form part of this application. The drawings, it is to be understood, illustrate merely a satisfactory embodiment of the improvement reduced to practice, and we are entitled to make all such changes therefrom as fall within the scope of what is claimed.

In the drawings:

Figure 1 is a plan view of an electrically heated iron in accordance with this invention, the handle being removed.

Figure 2 is a side elevation of the complete iron.

Figure 3 is a sectional view on the line 3—3 of Figure 1, a portion of the handle being illustrated.

Figure 4 is a plan view of the thermostatically influenced spring and the indicator hand.

Figure 5 is a rear end view thereof.

Figure 6 is a perspective view of the crank shaft engaged by the spring.

Figure 7 is a perspective view of the thermostatically influenced spring.

As disclosed by the drawings, we construct

our iron to include a base 1, which may be of steel, hardened iron or any other desired material. The base 1 has its point and sides provided with a continuous inwardly inclined flange 2, and within the flange and resting on the top of the base is the heating unit 3. The heating unit is encased in a suitable insulating member 4.

Received within the flange 2, and resting on the upper surface of the insulating facing 4 for the heating unit 3 is a core 5. The core is constructed of some suitable heat retaining material and has its outer surface shaped to correspond with the inclined sides, front and rear of the base 1. On the core 5 is a hollow member in the nature of a cap 6. The cap is shaped to snugly receive the core therein and has its lower edge resting on the straight upper face of the flange 2 of the base 1, its rear portion, however, being extended and received between the side flanges of the base and in contacting engagement with the upper face of the base proper. This portion, indicated for distinction by the numeral 6', also is in contacting engagement with the end of the insulating facing for the heating unit 3.

At determined spaced points the base 1 has threaded openings therethrough, and in a line with these openings the core 5 is provided with elongated openings 7. The openings 7 communicate with pockets 8, formed from the outer face of the core, and also with openings 9 in the top of the cap 6. Passing through these openings are bolts 10. The heads of these bolts are preferably provided with kerfs 11 whereby a screw driver may be employed for turning the same. The heads of the bolts also contact with washers 12 that are disposed on the outer face of the cap 6.

Secured on the bolt 10, and in contacting engagement with the inner walls of the pockets 8 are nuts 13. On these nuts are washers 15. Surrounding the bolts and contacting with the washers are helical springs 16. The bolts pass through openings in the angle base portions 17 of arms 18 that pass through openings in the cap 6 and between which the handle 19 of the iron is secured. The springs contact with the under face of the arms 17 and hold the said arms tight against the under face of the cap and also hold the nuts 13 from turning.

Conductors 20 lead from the heating unit to binding posts 21 secured in insulating

members 22 at the rear and inclined portion 23 on the top of the cap 6. Each binding post is provided with an extension 24 to receive the usual plugs connected to the conductors which are attached to the floor or wall plugs, and the members 24 are surrounded by a shield 25.

Approximately centrally between the bolts 10 the core is provided with a round depression forming a pocket 26. The top of this pocket is widened, and on the flange thus provided there rests a dial 27. The dial is surrounded by a suitable case of bezel 28 that carries a transparent plate 29. In the pocket 26 there is journaled the reduced end 30 of a crank shaft 31, the outer straight end of the said shaft being journaled through a bearing opening in the dial plate 27. On this end there is secured an indicator hand 32 which is arranged over the dial plate. By reference to Figures 1 and 3 of the drawings, it will be seen that the crank shaft 31 is disposed near the rear wall of the pocket 26.

Secured to one of the side walls of the pocket 26 is one arm 33 of a substantially U-shaped spring. The second arm 34 of the spring has its end given a half twist, as at 35 to provide a flat extension 36 which is 30 bifurcated as at 37 to receive the crank portion 38 of the shaft 31. The U-shaped spring is constructed of laminated metal and is, of course, thermostatically influenced. On the dial plate, at the index end of the hand 32 35 we inscribe suitable indicia, such as "Cold," "Warm," "Hot," "Very hot," and "Dangerous". By regulating the switch which controls the current between the house supply and the iron proper heating of the iron 40 can be obtained, and the degree at which the iron is heated will be readily apparent to the operator, and it is thought that the foregoing description, when taken in connection with the drawings will amply set forth the 45 construction, operation and advantages of the improvement.

Having described the invention, we claim:-

1. In an electrically heated sad iron, a flanged base, a heating unit therein, an insulating casing enclosing the unit, conductors for the unit, a heat retaining core re-

ceived in the flange of the base and resting on the insulating casing, a cap surrounding the core, and a thermostatically influenced indicator in the core and visible through the cap, a handle, and removable means securing the handle, cap and core to the base.

2. In an electrically heated sad iron, a flanged base, a heating unit therein, an insulating casing enclosing the unit, conductors for the unit, a heat retaining core received in the flange of the base and resting on the insulating casing, a cap enclosing the core, a handle, removable means securing the handle, cap and core to the base, a crank shaft in the core, a thermostatically influenced laminated spring having a portion secured in the core and another portion engaging the crank of the shaft, an indicator hand on the shaft, a dial over which the indicator is arranged, a bezel over the dial extending through the cap, and a transparent plate closing the bezel.

3. In an electrically heated sad iron, a flanged base, a heating unit enclosed in an insulating casing which rests on the base between the flanges thereof and fully covers such portion of the base, a core of heat retaining material received between the flanges of the base and resting on the insulating casing, conductors for the heating unit, binding posts for the conductors, a guard surrounding the binding post, a cap surrounding the core and to which the guard is secured, a handle, means removably securing the cap, handle and core to the base, means locking said securing means, said core having a pocket therein, a dial plate in the pocket, a crank shaft journaled in the pocket and dial plate, an indicating hand on the outer end of the crank shaft over the dial plate, a laminated thermostatically influenced substantially U-shaped spring having one end secured in the pocket and its other end twisted and bifurcated to receive the crank portion of the crank shaft, a bezel over the dial plate, and a transparent fac-

ing for the bezel.

In testimony whereof we affix our signatures.

JOHN W. MCGILVRAY.
JOSEPH WELLERSDICK.
